UNITED STATES PATENT OFFICE

2,020,354

GAME APPARATUS

Louis W. Gensburg, Chicago, Ill.

Application June 14, 1934, Serial No. 730,638

1 Claim. (Cl. 273—121)

My invention relates to certain novel improvements in a game apparatus and has particular reference to a new and novel ramp therefor for guiding balls projected upon the board of the apparatus to a position for gravitation down the board and has for its principal object the provision of an improved construction of this character which will be highly efficient in use and economical in manufacture. Heretofore in constructing the cabinets for game apparatus such as are known in the trade as coin controlled pin games it was the custom to cut from suitable lengths of material semi-circular plates which when finished and mounted upon the play board at opposite ends provided what is known as the ramps designed and adapted to guide balls upon the play board in position for gravitation thereover and along. Before these plates could be applied in their respective positions upon the play board it was essentially necessary that the circular edge or edges of these plates be absolutely true and free from roughness or other protuberances otherwise due to the roughness or protruding parts or elements the balls when guided by the circular ramps would be deflected prematurely upon the game board for gravitation thereover and along. Considerable labor and expense is involved in the production of wooden ramps which I have referred to and it has been the custom in order to overcome the difficulties mentioned to line the circular edges with metal securing the metal lining or facing to the plates by means of screws or the like. This increased the cost of manufacture of the game apparatus.

It is therefore one of the many objects of this invention to provide a ramp which is of a continuous single unitary element thereby making it unnecessary to finish the circular edges of plates and making it further unnecessary to determine whether such edges are free from roughness or protruding elements or portions.

A still further object of the invention is the provision of a ramp constituting a single unit which greatly facilitates the assembly of the ramp and its filler blocks upon the play board of the game apparatus.

Other objects will appear hereinafter.

The invention consists in the novel combination and arrangement of parts herein described and claimed.

The invention will be best understood by a reference to the accompanying drawing illustrating the preferred form of construction of the invention and in which:

Fig. 1 is a plan sectional detail view of a game

apparatus illustrating my improved ramp associated therewith;

Fig. 2 is a fragmentary perspective view of the same;

Fig. 3 is a sectional detail view of the same taken substantially on line 3—3 of Fig. 1; and

Fig. 4 is a fragmentary sectional detail view of the same taken substantially on line 4—4 of Fig. 2.

Referring more particularly to the drawing in 10 which there is illustrated the preferred form of construction of my invention 10 indicates a cabinet which includes a play board 11 upon which play board 11 balls (not shown) are adapted to be projected along and from a ramp 12. This 15 ramp 12 includes two straight sections 13 and 14 joined together at corresponding end portions as an integral unit by a circular ramp section 15. The opposite end portion of the straight ramp section 13 merges into a filler block 16 which 20 extends in a substantial alignment with the circular ramp section 15 and completes the connection between the end 17 of this straight ramp section 13 and the adjacent wall 18 of the cabinet. The opposite end portion of the straight 25 ramp section 14 merges into a circular ramp portion 19 which is defined by a radius less than the radius defining the circular ramp section 15 whereby to provide between the end 20 of this circular ramp section 19 and the end 17 a suitable 30 passage for the projection of balls upon the play board 11 by a projecting device (not shown).

The ramp as is evident from the description herein is formed of a single continuous piece 35 or length of material and as shown in the drawing is substantially channel shaped in cross section with the bight portion 21 of the ramp providing the guiding surface for the balls. The ramp is positioned upon the play board 11 as 40 shown in Fig. 1 and to complete the invention there are provided filler blocks 22 disposed at the opposite corresponding end portions of the play board with their circular edged portions 23 snugly fitted into the channel of the ramp thus serving to retain the shape of the ramp particularly the circular ramp portions thereof. These filler blocks are secured to the play board 11 by suitable attaching elements 25. In order to assure parallel relationship between the straight ramp 50 portions of the ramp and to prevent these portions from buckling due to temperature changes when the straight ramp portions are of considerable length they may be attached to the play board through the medium of suitable securing 55

elements 24 in the form of wood screws or the like.

By the use of a ramp such as is herein described it is obvious that a great saving results in the construction of the game apparatus and that a truer guiding wall or surface results for guiding the balls in position to gravitate upon and over the game board and that the assembly of the several parts thus described is of a maximum 10 simplicity.

While I have illustrated and described the preferred form of construction of my invention, this is capable of variation and modification, without departing from the spirit of the invention. I, 15 therefore, do not wish to be limited to the precise details of construction set forth, but desire to avail myself of such variations and modifications as come within the scope of the appended claim.

Having thus described my invention what I claim as new and desire to protect by Letters Patent is:

A ramp for a play board of a game apparatus comprising a member formed from a single length of material and said member being substantially channel-shaped in cross section throughout its entire extent with the said member formed to provide oppositely disposed semi-circular ramp portions with one of the semi-circular ramp portions being defined by a radius less than the length of the radius defining the other semi-circular ramp portion, and filler blocks having semi-circular edge portions mounted in the channels of the said semi-circular ramp sections. 10 15
